Fig. 3.

UNITED STATES PATENT OFFICE.

JOHN J. CATRON, OF BONHAM, TEXAS.

FLUID DISPENSER.

Application filed August 18, 1919. Serial No. 318,339.

To all whom it may concern:

Be it known that I, JOHN J. CATRON, a citizen of the United States, residing at Bonham, in the county of Fannin and State 5 of Texas, have invented certain new and useful Improvements in Fluid Dispensers, of which the following is a specification.

This invention relates to new and useful improvements in fluid dispensers.

10 The invention has to do particularly with improvements and additions relating to my Letters Patent No. 1,301,385, issued April 22, 1919.

One of the improved features is an automatic drain for the accumulating cylinder whereby said cylinder is drained when the dispenser is closed; and whereby the operating mechanism is unoperable until the dispenser is again opened and the drain 20 valve fully closed. Such an arrangement makes for safety as well as accuracy.

Another feature includes an accumulating cylinder to which the liquid is delivered under pressure after having been measured 25 thru the meter; and from which cylinder the liquid is discharged by gravity thru an outlet valve. This arrangement obviates air pressure in the drain hose and makes for a smooth and rapid discharge.

30 One of the improvements over the aforesaid Letters Patent is the substitution of a hand valve for the foot operated air release valve, said hand valve being located close to the operating lever and making for greater 35 convenience and simplicity. In this connection is also included a pressure relief valve, set to open at a given pressure and arranged so as to operate either when the controlling and air release valves are opened 40 or closed.

Other features will be hereinafter more particularly brought out.

The invention will be more readily understood from a reading of the following 45 specification and by reference to the accompanying drawings, in which an example of the invention is shown and wherein:

Fig. 1 is an elevation of a dispenser constructed in accordance with the invention,

50 Fig. 2 is a side elevation of the controlling and measuring mechanism,

Fig. 3 is a front elevation of the same,

Fig. 4 is a sectional detail of the liquid control valve,

55 Fig. 5 is a sectional detail of the air release valve,

Fig. 6 is a sectional detail of the master air valve,

Fig. 7 is a detail of the liquid control valve, and

Fig. 8 is a detail of the air control valve.

In the drawings the numeral 1 designates a liquid discharge pipe and 2 a compressed air delivery pipe. These pipes are arranged to be connected with the gasoline discharge 65 pipe and the air pressure pipe of a suitable storage tank, such as the storage tank shown in my co-pending application filed May 2, 1919, Serial No. 294,277, which has issued in Patent No. 1,352,788, or any other 70 equivalent structure. The pipes 1 and 2 are connected to couplings 3 and 4 respectively. The couplings are connected by a hollow cross member 5 which, however, communicates only with the coupling 4. A pipe 6 75 including a number of elbows extends upward in rear of the pipe 1 and is carried over and down in front thereof to a point of connection with the hollow cross member 5. This pipe provides a vent for the storage 80 tank with which the dispenser is used. A normally open hand valve 7 is connected in the pipe 6 and includes a spring pressed valve plunger 8, which is shown in its depressed or closed position in Fig. 5.

85 A liquid control valve 9 is connected to the upper end of the coupling 3 and an air control valve 10 is mounted on the coupling 4. An air supply pipe 11 is bent at right angles and leads from a master air 90 valve 12 to the valve 10. This master valve is shown in detail in Fig. 6. This valve has a spring pressed valve head 13 operated by a detent 14 which is engaged by the inner end of an arm 15 pivoted on the valve. The 95 valve 9 has a tapered plug 16 with an opening 17 therethru; while the valve 10 has a tapered plug 18 provided with an air port 19 extending therethru and connecting with a triangular duct 20 in the surface of said valve. These valves are provided with an operating lever 22 mounted therebetween. The upper end of the lever engages the arm 15 of the master valve when the lever is swung to open the liquid and air valves as 105 in said Letters Patent No. 1,301,385.

An elbow 23 leads from the top of the valve 9 to a suitable meter 24 from which a discharge pipe 25 leads to a T 26. A short pipe 27 connects the T 26 with an accumulating cylinder 28, preferably of glass. A discharge pipe 29 leads from one branch of

the T 26 and has an ordinary globe valve 30 connected therein. An elbow 31 is connected to the end of the pipe 29 and a service hose 32 leads from the elbow; said hose having a nozzle 33 at its end. An air vent pipe 34 leads from the top of the elbow to the top of the cylinder.

In the center of the cylinder an overflow pipe 35 is arranged and has a section 36 leading down to an elbow 37 which is mounted on the upper end of a section 37' leading back to the storage tank. From the T 26 a second drain pipe 38 leads to the elbow 37. An ordinary rotary cut-off valve 39 similar to the valve 9 is connected in the pipe 38 and this valve is normally closed to prevent the liquid from the cylinder draining back into the pipe 37'. A lever 40 is secured to the stem of the valve 39 and has its lower end pivoted to the upper end of a link 41 having its lower end connected with an ear 42 projecting laterally from a vertically slideable rod 43, said rod being supported by the link. A cross-bar 45 is suitably fastened to the inner side of the door 46 of the cabinet 47 in which the mechanism is enclosed. The bar 45 is positioned so that the door 46 must be entirely lowered and the valve 39 entirely closed, to permit the handle lever 22 to pass said bar. If the valve 39 remained partly open liquid would flow back into the drain pipe 37' when it was being dispensed thus defrauding the customer. When the door is slid up to close the cabinet the bar 45 engages the ear 42 and pushes the link 41 upwardly thereby swinging the valve lever 40 and opening the valve 39.

As before stated the device is to be used in connection with a suitable storage tank. The master air valve 12 is connected with an air supply pipe 48 which receives compressed air from a suitable source and thru a pressure reducing valve 49.

In using the dispenser the operator depresses the plunger 8 of the valve 7 with one hand and grasps the handle lever 22 with the other hand. This closes the air vent or exhaust. By swinging the lever 22 upward the valve 9 is first opened and when the upper end of the lever engages the arm 15 the master air valve 12 is opened, whereby compressed air flows thru the pipe 11 and past the valve 10 and thru the pipe 2 to the storage tank. Liquid is forced out thru the pipe 1. The exact operation of these parts will be understood when considered in connection with the disclosure in the Letters Patent No. 1,301,385 before referred to. The liquid is forced by the compressed air thru elbow 23, pipe 25, T 26 and pipe 27 to the accumulating cylinder 28. When a predetermined quantity of liquid has passed the meter the handle 22 is swung down to cut-off the supply of liquid and air and the operator releases the valve 7 whereby the

air pressure below the valves 9 and 10 is vented. So long as the valve 7 is held closed by the operator the air in the cross-member 5 and pipe 2, acts to elevate the liquid, but when the operator releases the valve, the air from the pipe 2 and member 5 passes out through the pipe 6.

The nozzle 33 having been placed in the receptacle to which the liquid is to be delivered, the operator opens the valve 30 whereby the liquid in the cylinder 28 flows by gravity down thru pipe 27, T 26, pipe 29, elbow 31, hose 32 and is discharged from the nozzle 33.

It will be seen that an absolutely safe dispenser is had. The ease and rapidity of operation is apparent and the high degree of accuracy makes the dispenser efficient.

What I claim, is:

1. In a liquid dispenser, a liquid supply pipe, a meter connected in the supply pipe, a liquid controlling valve connected in the supply pipe in advance of the meter, an accumulating receptacle, a valve controlling the flow of the liquid from the receptacle, a compressed air supply pipe, a compressed air delivery pipe for supplying air to force the liquid through the supply pipe, an air vent connected with the compressed air delivery pipe and normally open, and means for closing said vent when air is supplied to the delivery pipe.

2. In a liquid dispenser, the combination of a cabinet having a movable door, a liquid accumulating receptacle carried by the cabinet, means for supplying a liquid to the receptacle, means for dispensing the liquid from the receptacle, a drain pipe leading from the receptacle, a valve controlling the drain pipe, means for operating the valve automatically operated by the door of the cabinet, and means controlled by the door acting to prevent the operation of the liquid supply means until the drain valve is entirely closed.

3. In a liquid dispenser, the combination with a cabinet having a movable door, a measuring receptacle carried by the cabinet and means for supplying liquid to the receptacle, of means for controlling the passage of liquid to the receptacle and the discharge of said liquid from the receptacle, including a drain valve automatically operated by the door to prevent the passage of liquid through the receptacle and its discharge therefrom, until the drain valve is entirely closed.

4. In a liquid dispenser, a cabinet having a movable door, a liquid accumulating receptacle, means for supplying the liquid to the receptacle, an outlet conduit having communication with the liquid accumulating receptacle and adapted to convey the liquid to a point exteriorly of the receptacle, a drain valve for the liquid

5 accumulating receptacle and connected with the door to be completely closed when the door is entirely opened, and means controlled by the movement of the door to prevent the passage of the liquid from the liquid supply means through the accumulating receptacle into the outlet conduit, until the drain valve is completely closed.

- 10 5. In a liquid dispenser, a cabinet having a movable door, a liquid accumulating receptacle, means for supplying a liquid to the receptacle, means for dispensing the liquid from the receptacle, a drain valve having communication with the receptacle, means
15 for connecting the drain valve with the door so that the drain valve is operated by the door, and means controlled by the door act-

ing to prevent operation of the liquid supply means when the door is shifted to a selected position.

20

6. In a liquid dispenser, an accumulating cylinder, a three way T connected in the bottom of said cylinder, a liquid supply pipe connected with said T, an overflow pipe extending downwardly from the cylinder, a drain pipe extending from the T to the overflow pipe, a drain valve in said drain pipe, a dispensing conduit connected with said T, a dispensing valve included in said conduit, and means for automatically operating said drain valve.

25

In testimony whereof I affix my signature.

JOHN J. CATRON.
